VENETIAN BLIND CONSTRUCTION

Harry S. Rosenbaum, Baltimore, Md., assignor to
The Eastern Venetian Blind Company, Baltimore, Md., a corporation of Maryland

Application July 27, 1951, Serial No. 238,803

10 Claims. (Cl. 160—175)

1

The present invention relates to a Venetian blind tilt assembly employing a novel tilting mechanism. The novel tilting mechanism described herein comprises an end plate and a rotatable wheel attached thereto with spaced flat portions, whereby upon rotation of the wheel on its flat portions angular adjustment of the Venetian blind is effected.

Practically all of the presently known Venetian blinds utilize the conventional gear-type tilting assembly. However, such an assembly is expensive to manufacture which results in prohibitive costs of the Venetian blind to the ordinary consumer.

It is one of the general objects of the present invention, therefore, to provide a novel tilting assembly that both lends itself to ease in manufacturing and is economically desirable.

A second general object of the present invention is to provide a tilting mechanism which incorporates a novel tilting wheel having spaced flat portions formed therearound for determining the angular position of said wheel.

Another object of the present invention is to provide an end plate to which the wheel is secured, the end plate being formed in a very simple manufacturing process.

Still another object is to provide an operating cord that is operatively attached to the tilting wheel whereby upon manual movement of the operating cord, the tilting wheel will be rotated, thus effecting an angular adjustment of the slats in the Venetian blind.

Other objects and the nature and advantages of the instant invention will be apparent from the following description taken in conjunction with the accompanying drawings, wherein:

Fig. 1 is a front elevation of a Venetian blind assembly employing the present invention;

Fig. 2 is a front elevation of the novel tilting wheel assembly;

Fig. 3 is a line taken along 3—3 of Fig. 2 looking in the direction of the arrows with parts broken away;

Fig. 4 is a section taken along 4—4 of Fig. 3 looking in the direction of the arrows showing the tilting wheel being lifted and rotated from one flat portion to an adjacent flat portion; and

Fig. 5 is a view similar to Fig. 4 showing the tilting wheel after completion of the lifting and turning movement to the adjacent flat portion.

Referring to the drawings, and particularly to Fig. 1 thereof, the novel tilting apparatus 10 involved in the present invention, is disclosed in its operating position with a Venetian blind unit.

2

An operating cord 11 is actuated in the usual manner to move the slats upwardly or downwardly, as desired. To effect this movement of the slats, the operating cord 11 extends over pulleys 12, 13, down between the slats and connects to a base plate (not shown). A tilting slat 14 is connected to the novel tilting apparatus 10 and serves to tilt the blind to the different angular positions. Tapes 15, 16 combine with the tilting slat 14 to effect the tilting movements.

Referring to Figs. 2 and 3, the novel tilting apparatus is shown with an end plate 20 having side sections 21 and 22 perpendicular thereto. A vertically extending slot 23 is formed substantially in the center of the end plate 20, while a horizontal portion 24 is shown punched out from and bent at a right angle to the end plate 20. A slot 25 is formed as a result of the punched out portion 24. A pulley 26 is suitably attached to the end plate 20 in the upper left-hand corner, as viewed in Fig. 2. A tilting wheel A is formed from a pair of elements which are defined as a driven element 27 and a driving element 30 which are secured together as hereinafter described. The driven element 27 is shown as a hollow cylindrical body with oppositely disposed openings 29 and 36 formed in a rear flange 28 and the front face of the body, respectively. As seen in Fig. 2, a pin 35 extends loosely through the openings 29 and 36 into the slot 23, in which it is vertically movable. It is apparent that the tilting wheel A which comprises the driving element 30 and driven element 27 is rotatably mounted on the pin 35 and is vertically movable therewith. Longitudinal movement of the tilting wheel A is prevented by enlarged portions 37, 37' formed on the ends of the pin 35.

The driven element 27 of the tilting wheel A has a flange 28 integrally formed thereon which abuts against the end plate 20 and which has spaced therearound three flat portions 50, 51 and 52. The driving element 30 of the tilting wheel A is formed with an out-turned or flared flange 30a which extends outwardly from an inner driving element plate 30b. Cut out from the plate 30b and formed perpendicular thereto is a cut-out portion 38 shown particularly in Fig. 2. The driven element 27 and the driving element 30 are secured together by placing the driving element plate 30b flush against the front face of the driven element 27 with the flange 30a abutting against the outside edge thereof. Ears 33, 34 are cut out from the front face of the driven element 27 and are bent perpendicular thereto. The ears 33, 34 fit into grooves 31, 32 formed in the plate 30b.

and are lapped over the front of the plate 30b securing the driven element 27 and driving element 30 together and thereby forming single tilting wheel A.

Referring to Fig. 3, it is seen that a groove is formed by the flange 28 of the driven element 27 and the flared flange 30a of the driving element 30. The groove thus formed is adapted to receive operating cords 40, 41 as will be described more fully hereinafter.

The pin 35 loosely secures the tilting wheel A to the end plate 20, allowing said wheel to move upwardly and downwardly in the slot 23 and also allowing the wheel to rotate around its axis. The tilting wheel A disclosed particularly in Fig. 3, rests on the horizontal punched out portion 24 on one of the flat portions 50, 51, 52. In Fig. 3 the tilting wheel rests on the flat portion 52.

A cut-out section 33 is formed as part of the driving element 30 and is attached to a tilting slat 39 by suitable means. Hence, as the tilting wheel is rotated, the tilting slat 39 will be angularly adjusted accordingly.

The pulley 26 accommodates the two operating cord pieces 40, 41 which fit around the tilting wheel A in the groove formed by the flange 28 and the flared flange 30a of the driving element 30 of the tilting wheel. The operating cord pieces 40, 41 are connected to the driving element 30 at 43, 44 in the slot 42 which is formed in the flared flange 30a. It will be seen that as either of the said operating cords is moved the tilting wheel A will be rotated in the desired direction.

The tilting wheel A has three basic operating positions, the positions being determined by the flat portions 50, 51 and 52. In order to rotate the tilting wheel A from one flat position to another, thus changing the angle of the tilting slat 39, it is necessary that the tilting wheel A be lifted upwardly and over the flat portion upon which it is resting and rotated so as to reach the next flat portion. It is for this reason that the vertically extending slot 23 is provided. Thus by pulling on one of the operating cords, the tilting wheel A will be moved upwardly in the slot 23 and rotated around its axis to the next flat portion.

Figs. 4 and 5 show the inner portion 27 of the tilting wheel A in two positions, Fig. 4 disclosing the tilting wheel A between two flat portions, with the pin 35 located at an intermediate position in the vertically extending slot 23. As either of the operating cord pieces 40, 41 is pulled, which movement serves to rotate the tilting wheel A in a counterclockwise direction, as shown by the arrow in Fig. 4, the tilting wheel A will be lifted upwardly and rotated into the next flat position, which, in Figs. 4 and 5, is shown as flat portion 51. As the tilting wheel A rotates, the tilting slat 39 will be angularly adjusted, thus adjusting the position of the other blind slats.

In operation, the tilting wheel A rests on one of the flat portions 50, 51, 52. When an angular adjustment of the blind slats is desired, one of the operating cord pieces 40 or 41 is pulled with the resulting angular adjustment of the blind effected, as described above.

It will be obvious to those skilled in the art that the novel tilting apparatus described herein presents a device that is not only mechanically simple to operate but one that can be fabricated by a relatively uncomplicated manufacturing process. For example, the end plate 20 can be formed in one operation, the side sections being turned, the portion 24 punched out and the vertically extending slot cut to shape. Since very few

operating parts are necessary in the novel tilting apparatus, failure in operation even after long periods of use will be practically eliminated. The simplicity of fabrication of the present invention will consequently reduce manufacturing costs and as a practical result will make Venetian blinds available to those individuals who might find ordinary Venetian blind costs prohibitive.

It will be obvious to those skilled in the art that various changes may be made without departing from the spirit of the invention and therefore the invention is not limited to what is shown in the drawings and described in the specification but only as indicated in the appended claims.

What is claimed is:

1. In a Venetian blind tilt assembly, a plate having a vertically disposed slot formed therein, a horizontal shelf formed integral with said plate, a cord receiving pulley secured to said plate, a wheel disposed on said shelf, a pin secured to said wheel and extending through said slot for securing said wheel to said plate for vertical movement therewith, said wheel having a rear flange and a front flange, said rear flange being formed with flat portions equally spaced therearound, a tilting slat secured to said front flange, said flat portions formed on said rear flange defining different angular positions of said tilting slat, and an operating cord engaging said pulley and secured to said front flange, said operating cord rotating and lifting said wheel so that the desired flat portion of said rear flange engages said shelf, said tilting slat rotating with said wheel to effect a desired angular position.

2. In a Venetian blind tilt assembly, a plate, a tilting wheel, means joined to said plate for receiving said tilting wheel, slat means secured to said tilting wheel and rotating therewith, said wheel having flat portions formed thereon at predetermined positions defining various angular positions of said slat means, and operating means secured to said wheel for rotating said wheel so that one of said flat portions formed on said wheel is disposed on said receiving means, thereby effecting the desired angular position of said slat means.

3. In a Venetian blind tilt assembly, a plate, a tilting wheel secured to said plate for vertical movement therewith, a shelf joined to said plate for receiving said tilting wheel, a tilting slat secured to said tilting wheel and rotating therewith, one edge of said wheel contacting said shelf, said edge being formed with arcuate sections and flat portions equally spaced therearound, said flat portions defining predetermined angular positions of said tilting slat, and operating means secured to said wheel turning said wheel to said flat portions, said wheel moving vertically upwardly as the arcuate sections ride over said shelf and moving downwardly as the next flat portion comes into contact with said shelf.

4. In a Venetian blind tilt assembly, an end plate having a horizontal shelf formed integral therewith and extending perpendicular thereto, said plate having a vertically disposed slot formed therein, a tilting wheel formed with an edge operatively engaging said shelf, means secured to said wheel and disposed in said slot thereby providing for vertical movement of said wheel with respect to said plate, said tilting wheel having flat portions formed around the edge which engages said shelf, a pulley secured to said end plate, a tilting slat secured to said wheel, and an operating cord operatively engaging said

pulley and secured to said tilting wheel, said operating cord lifting and turning said wheel on the axis thereof to move said tilting slat to predetermined angular positions, said predetermined angular positions being defined by said flat portions of said wheel contacting said shelf.

5. In a Venetian blind tilt assembly, an end plate having a horizontal shelf formed integral therewith, tilting means operatively engaging said end plate and positioned on said shelf, a tilting slat secured to said tilting means, said tilting means having a plurality of flat portions formed around the edge which is positioned on said shelf, said flat portions engaging said horizontal shelf and defining predetermined angular positions of said tilting means, and means to lift and turn said wheel so that one of said flat portions engages said shelf thereby defining an angular position of said slat.

6. In a Venetian blind tilt assembly, a plate, a shelf integral with said plate, rotatable means operatively secured to said plate, said rotatable means comprising a wheel, said wheel being formed with flat portions spaced around one edge thereof, each of said flat portions being adapted to engage said shelf and corresponding to predetermined angular positions of said rotatable means, a tilting slat secured to said wheel, and cord means operatively engaging said wheel for turning and moving said wheel thereby rotating said slat to said predetermined angular positions as defined by said flat portions.

7. In a Venetian blind tilt assembly, a plate having a vertically disposed slot formed therein, a shelf projecting from said plate formed integral therewith, rotatable means positioned on said shelf having flat portions spaced therearound, each of said flat portions defining a predetermined angular position of said rotatable means and engaging said shelf upon rotation of said rotatable means, a pin engaging said rotatable means loosely disposed in said slot and providing for vertical movement of said rotatable means, a slat means secured to said rotatable means, and a cord secured to said rotatable means for lifting and turning said rotatable means on said shelf thereby changing the angular position of said slat means.

8. In a Venetian blind tilt assembly, an end plate, a shelf joined to said plate, a tilting wheel secured for rotation to said end plate and vertically movable relative thereto, said tilting wheel having spaced flat portions formed therearound,

each of said flat portions being adapted to engage said shelf upon rotation of said wheel thereby defining predetermined angular positions of said wheel when said wheel is rotated, a tilting slat secured to said wheel, and an operating cord secured to said tilting wheel for lifting and rotating said tilting wheel on said shelf to move said tilting slat to said various predetermined angular positions.

10. 9. In a Venetian blind tilt assembly, an end plate having a vertically disposed slot formed therein, a pin positioned for vertical movement in said slot, a shelf joined to said plate, a tilting wheel positioned on said shelf, said pin secured to said tilting wheel and forming the rotating axis therefor, means formed on said wheel for causing vertical movement thereof when said wheel is rotated, slat means secured to said tilting wheel, and an operating cord secured to said tilting wheel for lifting and turning said wheel on said shelf to effect various angular positions of said slat means, said pin moving vertically in said slot upon rotation of said wheel thereby compensating for the vertical movement of said wheel.

15. 10. In a Venetian blind tilt assembly, an end plate having a vertically disposed slot formed therein, shelf means joined to said end plate, pin means positioned for vertical movement in said slot, tilting means secured to said pin means, slat means secured to said tilting means, said tilting means having flat portions spaced therearound to define different angular positions of said slat means when positioned on said shelf means, and 20 cord means secured to said tilting means for lifting and turning said tilting means to a flat portion on said shelf means to effect angular adjustment of said tilting means, said pin means moving vertically in said slot to compensate for the turning movement of said tilting means on said shelf means.

HARRY S. ROSENBAUM.
